ABSTRACT OF THE DISCLOSURE

A process and apparatus for removing the internal scarf from within a coil of welded tubing having a plurality of wraps which comprises filling the tubing with a substantially noncompressible liquid and applying a gas under pressure to force the liquid and scarf out of the tubing. A plug is normally provided intermediate the gas and the liquid. The plug traverses the wraps of the tubing to force the liquid and scarf out. A second plug may be provided at the outlet end of the tubing.

BACKGROUND OF THE INVENTION

This invention deals with an improved method and apparatus for removing the internal scarf and other foreign matter from the inside of long lengths of coiled tubing. Normally in a commercial operation the inside of coiled tubing must be cleaned prior to shipment to a customer for use. This is particularly true with respect to tubing made by welding an elongated strip.

It is conventional to remove the weld bead on the inside of the tubing, thereby leaving an internal scarf within the tubing. For straight lengths of tubing, removal of this internal scarf can usually be easily accomplished by using a blast of compressed air.

However, to remove the internal scarf from a long length of coiled tubing such that the tubing would be usable in the longest manufactured length, the use of an air blast or similar means to remove the scarf is not very effective and causes bunching and wadding of the internal scarf requiring several blowing operations to force the scarf out of the tube, and sometimes it is impossible to blow the scarf out.

SUMMARY OF THE INVENTION

In accordance with the present invention, it has been found that the problem of removing the internal scarf and other foreign matter from long lengths of coiled tubing can be substantially eliminated by first filling the tubing with a substantially non-compressible liquid such as water and then providing a plug at least at the inlet end of the coil followed by the application of a compressible gas at a relatively high pressure to the inlet end of the coil.

The substantially non-compressible liquid acts like a cylinder or ram as it moves through the coiled tubing and carries with it all the internal scarf and foreign matter which is contained within the liquid cylinder. The cylinder of liquid is moved by the action of the gas upon the plug which forces the plug and, therefore, the liquid through the coiled tubing.

The advantage of the process in accordance with this invention is the fact that the internal scarf moves with the liquid out of the exit end of the coiled tube without substantial bunching up or wadding which could form a blockage.

The apparatus in accordance with this invention includes means for filling the coiled tube with a substantial non-compressible liquid, plugs positioned within at least the inlet end of the coiled tube and means communicating with the inlet end of the coiled tube for applying a gas under pressure.

Accordingly, it is a principal object of this invention to provide a process for removing the internal scarf and foreign matter from coiled welded tubing particularly long lengths of such tubing.

5 It is a further object of this invention to provide an apparatus for carrying out the aforesaid process.

Other objects and advantages will become apparent to those skilled in the art as a detailed description follows with reference to the drawings.

10 BRIEF DESCRIPTION OF THE DRAWINGS

FIG. 1 shows in perspective a typical coiled tube to which this invention is applicable.

15 FIG. 2 shows sections of the coiled tube at each end of the coil after the tube has been filled with a substantially non-compressible liquid but before the application of the gas under pressure.

20 FIG. 3 shows a perspective view of a typical plug in accordance with this invention.

25 FIG. 4 shows a cross section of the coiled tube at each respective end during the blow out procedure.

DETAILED DESCRIPTION OF THE PREFERRED EMBODIMENTS

30 This invention is directed to a method and apparatus for removing the scarfed weld bead and other foreign matter from within long lengths of coiled welded tubing. The welded tubing in accordance with this invention is usually formed from metal strip which is shaped into the form of a tube followed by welding together of the strip edges.

35 Typical examples of prior art welding processes are set forth in U.S. Pat. Nos. 3,037,105, granted May 29, 1962; 2,794,108, granted May 28, 1957; and 2,818,488, granted Dec. 31, 1957. The aforesaid patents set forth methods of high frequency forge welding metal strip into tubing; however, this is not meant to be limitative of the invention and other methods of welding could be employed.

40 Apparatuses are also known in the art for removal of the weld bead on the inside surface of the tube. One specific example, not meant to be limitative of the invention, is set forth in U.S. Pat. No. 3,349,212, granted Oct. 24, 1967.

45 The weld bead which is removed from the inside surface of the tube is known in the art as "scarf" and generally travels along within the tubing after its removal and stays within it during coiling.

50 It is desirable for manufacturing economy to weld extremely long lengths of tubing. This is usually accomplished by coiling the welded tubing because of space limitations in the manufacturing facility and other reasons. The coiled tubing contains within it the scarf as aforesaid and this internal scarf and other foreign matter generally must be removed prior to redrawing and/or annealing or other further processing.

55 For straight lengths of tubing, the use of an air blast has been found to be effective to remove the scarf from the inside of the tube. See for example application Ser. No. 167,637, by D. T. Van Allman et al., filed July 30, 1971 and assigned to the assignee of the instant invention.

60 With long lengths of tubing in the form of a coil, however, an air blast is not an efficient method for removing the internal scarf and other foreign matter from within the coiled tubing. The use of an air blast subjects the internal scarf to bunching and wadding which makes it difficult to remove. It usually requires several blowing operations to force the scarf out if possible at all.

65 In accordance with this invention, the problems of the prior art processes have been overcome by first filling the coiled tubing with a substantially non-compressible liquid.

The use of a non-compressible liquid acts like a cylinder or ram when it is forced to move through and out of the tubing and thereby it carries with it substantially all the internal scarf and foreign matter which is contained within this cylinder of liquid. The cylinder of liquid is forced through and out of the tubing by means of a gas under pressure which is applied to a plug which is inserted at the inlet end of the coiled tubing. The plug has a diameter substantially the same as the inside diameter of the tubing or slightly less than the inside diameter. The plug will be described in more detail hereinafter.

The gas under pressure may continue to be applied to the coiled tubing after the plug has exited in order to remove any residual water or other liquid.

Referring to FIG. 1 and 2, there is shown schematically a typical coil of tubing 1 in accordance with this invention. The coil 1 can be supported by a cart C as shown or in any other desired manner. Further, the coil 1 may be disposed with the wraps vertical or horizontal or as otherwise desired. The coiled tubing 1 is filled from the inlet end 2 with water or other substantially non-compressible liquid 3. Any fluid pressure sufficient to force the liquid 3 to flow around the wraps 4 of the coiled tubing 1 and out of the exit end 5 may be employed up to the burst pressure of the tubing. Pressures of 20 to 50 p.s.i. have been found to be adequate. The terms inlet end 2 and outlet end 5 are used to indicate opposite ends 2 and 5 of the coiled tubing 1 is employed as the inlet end 2.

The water line W may be attached to the coiled tubing 1 by any conventional means, such as a fitting F or connector connected to a suitable hose. Alternatively, for example, a hose having an outside diameter slightly larger than the inside diameter of the tubing 1 may be forced into the tubing 1 or a hose having an inside diameter slightly smaller than the outside diameter of the tubing 1 may be clamped about the outside diameter of the tubing 1.

It is essential that the coiled tubing 1 be substantially filled up with the non-compressible liquid 3 prior to the application of the pressurized gas since this assures that the scarf 6 will be carried with the liquid 3 out of the tubing 1.

After the coiled tubing 1 has been filled with the liquid 3, a plug 7 is inserted in at least the inlet end 2 of the tubing 1 as shown in FIG. 2. It is only essential in accordance with this invention that a plug 7 be inserted in the inlet end 2 since the function of the plug 7 is to force the cylinder of liquid 3 out of the coiled tubing 1; however, a second plug 7' preferably is inserted in the exit end 5 of the tubing 1.

The purpose of the second plug 7' is to enable pressure to be built up against the first plug 7 and the column of liquid 3 so that the liquid may be forced out under a substantial pressure, preferably, at least 200 p.s.i. This is the most preferred approach for carrying out this invention and the one that works most successfully and consistently. The second plug 7' may be held in place by any conventional means such as a clamp or more simply by the use of tape, or other like restraining means 8.

A gas under pressure is applied to the first plug 7 at the inlet end 2 of the coiled tubing. The supply 10 of gas 9 under pressure is connected to the inlet end 2 of the tubing 1 by any conventional means as, for example, the use of a hydraulic chuck 11 which clamps about the tubing 1 and which is connected to the gas supply 10. The gas supply 10, suitably regulated by conventional means to provide the desired pressure, may come from a compressor or from tanks of compressed gas as desired. The particular gas which may be employed is a matter of choice; however, preferably, air or nitrogen are used since they are the most economical.

An exemplary hydraulic chuck 11 is Model No. HC8B, manufactured by Air Mo Hydraulics Inc. of Minneapolis, Minnesota, which is useful for one inch diameter tubing 1. Other models are available which are adapted to be

used with the various sizes of tubing 1 which may be encountered. The hydraulic chuck 11 is of conventional design and the one manufactured by Air Mo Hydraulics Inc. is merely set forth as being exemplary and is not meant to be limitative of the invention.

FIG. 3 shows a typical plug 7 in accordance with this invention. Generally, the plugs 7 or 7' at the inlet end 2 and outlet end 5 of the tubing 1 are of the same construction. The structure shown in FIG. 3 is merely exemplary and is not meant to be limitative of the invention. The plug 7 shown therein has a cylindrical shape with an outside diameter substantially equal to or smaller than the inside diameter of the coiled tubing 1 by as much as 0.050".

Other plug 7 shapes can be employed as desired. For example, balls have been used successfully; however, the shape shown in FIG. 3 is the most preferred and effective in accordance with this invention for tubing of circular cross section. For tubing of other than a circular cross section, the plug 7 would have a substantially corresponding cross section. The plug 7 shown is solid, however, plugs having a cup shape have also been found to be useful. For example, plastic sleeve cups of the type used on electrical conduits have been employed successfully when the flat end was positioned opposite to the direction of flow. Steel balls work well but are undesirable since they are dangerous as they exit the coiled tubing 1 at high velocity.

The plug 7 may be formed of any desired material; however, the most effective material for the plug 7 has been found to be Elastacast polyurethane, which is manufactured by Acushnet Company, Fort Worth, Texas. Elastacast has excellent chemical and abrasion resistance and is tough and resilient. The Elastacast is available in the form of rods of desired cross section and plugs 7 or 7' of any desired length can be cut from the rods. The plugs 7 or 7' preferably range in length from about 1/2" to about 1". The Elastacast has a degree of resiliency which provides a markedly improved wiping action when used in accordance with this invention, namely, it has been found that the use of an Elastacast plug 7 provides a squeegee type wiping action as the plug is forced through the tubing.

The gas pressure which is applied to the plug at the inlet end 2 of the tubing 1 to force it through the coil generally ranges up to 600 p.s.i. and preferably is from 350 to 500 p.s.i. Greater pressures up to the burst pressure of the tubing could be employed but are not deemed to be necessary.

Referring again to FIG. 2, it is seen that a gas pressure fitting 11 which preferably is a hydraulic chuck is attached to the inlet end 2 of the coiled tube 1. A valve 12 in the line 13 between the high pressure gas supply 10 and the fitting 11 allows the gas to be turned on and off. These elements then comprise an exemplary means for applying the gas under pressure to the plug 7 at the inlet end 2 of the tubing.

FIG. 4 shows the apparatus of this invention in operation. As shown in FIG. 4, the valve 12 in the gas line 13 has been opened and the restraining means 8 removed and the gas 9 under pressure has forced the plug 7 at the inlet end 2 to traverse the wraps 4 of the coiled tubing 1 to almost the outlet end 5 of the tubing 1. The second plug 7' has been blown out of the tubing 1 as shown. The liquid 3 flows out of the tubing 1 as shown and the scarf 6 separates from the liquid because of its greater weight as it exits the tubing 1 and is easily collected for reuse as scrap.

When the process is carried to completion, the plug 7 would also exit the tubing 1 in a manner similar to the plug 7'.

After the inlet end plug 7 has exited from the tubing 1, the flow of gas may be continued through the tubing 1 to remove any liquid 3 which may have been retained. It has been found, however, that the use of an Elastacast plug 7 by virtue of its squeegee action provides a substan-

tial'y clean surface leaving little or no liquid in the tubing. This invention is applicable to coiled tubing 1 having a wide range of outside diameters and, preferably, to tubing 1 having a diameter of $\frac{1}{2}$ " to $3\frac{1}{8}$ " and, most preferably, to tubing having a diameter of $\frac{3}{4}$ " to $1\frac{1}{8}$ ". The inside diameter of the tubing 1 may vary depending on tube wall thickness.

In accordance with this invention, it is possible to remove the scarf 6 from coils 1 of very substantial length, preferably, up to 5,000 ft. long and, most preferably, up to 2,500 ft. long. Generally, the coils range from 1,000 to 3,000 ft. in length. This represents a marked improvement over prior processes where the coiled tubing 1 has to be cut into short lengths of a few hundred feet in order to be able to be cleaned.

The diameter of the coils 1 will vary depending on the diameter of the tubing and the particularly coiling apparatus which has been employed. The process is preferably applicable to coils 1 having an outside diameter of up to 200" and has found particular use with coils of a diameter of 36" to 100". The inside diameter of the coil should preferably range from about 20" to about 190" and, preferably, from 20" to 96".

The tubing preferably is formed of copper or copper base alloys, aluminum or aluminum base alloys, iron or iron base alloys, or nickel or nickel base alloys.

The substantially non-compressible liquid 3, may contain any desired additives such as, for example, corrosion inhibitors.

This invention may be embodied in other forms or carried out in other ways without departing from the spirit or essential characteristics thereof. The present embodiment is therefore to be considered as in all respects illustrative and not restrictive, the scope of the invention being indicated by the appended claims, and all changes which come within the meaning and range of equivalency are intended to be embraced therein.

What is claimed is:

1. A process for removing the internal scarf from within a coil of tubing having a plurality of wraps and inlet outlet ends comprising:

substantially filling up said tubing with a substantially non-compressible liquid; providing a first plug in said inlet end of said tubing, of said plug having a diameter slightly less than or substantially the same as the inside diameter of said tubing, and contacting said liquid; and applying a gas under pressure to said inlet end of said tubing and against said plug so as to force said plug to traverse the wraps of said tubing and thereby force said liquid and said scarf out of the outlet end of said tubing.

2. A process as in Claim 3 wherein intermediate said filling and said gas application steps a second plug is provided in the outlet end of said tubing; and wherein said second plug is restrained from being forced out of said tubing during said gas application step until the pressure on said first plug has built up to at least 200 p.s.i.

3. A process as in Claim 2 wherein the length of said tubing in said coil is less than 5,000 ft. long.

4. A process as in Claim 3 wherein the length of said tubing in said coil is between 1,000 and 3,000 ft. long.

5. A process as in Claim 3 wherein said gas under pressure comprises nitrogen.

6. A process as in claim 3 wherein said gas under pressure comprises air.

7. A process as in Claim 5 wherein said substantially non-compressible liquid comprises water.

8. A process as in Claim 6 wherein said substantially non-compressible liquid comprises water.

9. A process as in Claim 7 wherein said gas pressure comprises 350 to 500 p.s.i.

10. A process as in Claim 8 wherein said gas pressure comprises 350 to 500 p.s.i.

11. A process as in Claim 9 wherein after said first plug has exited from said tubing the step of applying said gas under pressure is continued until substantially any residual amount of said liquid remaining in said tubing has been removed.

12. A process as in Claim 10 wherein after said first plug has exited from said tubing the step of applying said gas under pressure is continued until substantially any residual amount of said liquid remaining in said tubing has been removed.

13. An apparatus for removing the internal scarf from within a coil of tubing having a plurality of wraps and inlet and outlet ends comprising:

means for substantially filling up said tubing with a substantially non-compressible liquid;

a first plug inserted in said inlet end of said tubing after the filling of said tubing with said non-compressible liquid so as to contact said liquid, said plug having a diameter slightly less than or substantially the same as the inside diameter of said tubing; and

means for applying a gas under pressure to said plug so as to force said plug to traverse the wraps of said tubing and thereby force said liquid and said scarf out of the outlet end of said tubing.

14. An apparatus as in Claim 13 wherein said means for applying said gas to said plug comprises a supply of gas under pressure which is connected to the inlet end of said tubing.

15. An apparatus as in Claim 14 wherein a valve is provided intermediate said gas supply and said inlet end of said tubing to enable the gas under pressure to be turned on and off.

16. An apparatus as in Claim 14 wherein a second plug is provided in the outlet end of said tubing and wherein a restraining means is provided for preventing said second plug from being forced out of said tubing when said gas is applied until the pressure on said first plug has built up to at least 200 p.s.i.

17. An apparatus as in Claim 16 wherein the pressure of said gas from said supply comprises 350 to 500 p.s.i.
